(57) CLAIM

The ornamental design for a combination double-sided shower brush, as shown and described.

DESCRIPTION

FIG. 1 is a front perspective view of a combination double-sided shower brush, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of area 9 in FIG. 1;

FIG. 10 is a front perspective view showing the combination double-sided shower brush in an open state; and,
FIG. 11 is a front perspective view showing the combination double-sided shower brush in a separated state.

The even length broken lines in the drawings illustrate the portions of the combination double-sided shower brush that form no part of the claimed design.

The dot-dash-dot broken lines encircling the enlarged views depict the boundaries of the enlarged views and form no part of the claimed design.

The "BUBBLEDDANCE" lettering and icon forming part of the disclosure is a registered trademark of Shanghai Nuoran Intelligent Technology Co., Ltd.
